Primary Examiner — Keli L Hill(74) *Attorney, Agent, or Firm* — Muncy, Geissler, Olds & Lowe, P.C.(57) **CLAIM**

The ornamental design for a combined container and confection, as shown and described.

DESCRIPTION

FIG. 1 is a front view of a combined container and confection showing my new design;

FIG. 2 is a rear view thereof;

FIG. 3 is a left side view thereof;

FIG. 4 is a right side view thereof;

FIG. 5 is a top plan view thereof; and,

FIG. 6 is a bottom plan view thereof.

In the drawings, the broken lines depict portions of the combined container and confection that form no part of the claimed design.

The oblique shade lines depict a transparent or translucent surface or material.

1 Claim, 3 Drawing Sheets(56)
